TRAIN ORDER DELIVERY DEVICE

Carl S. Adams, Minneapolis, Minn., assignor of
one-half to Clinton A. Glenn, Minneapolis,
Minn.

Application May 3, 1935, Serial No. 19,697

4 Claims. (Cl. 258—2)

My invention provides an extremely simple and highly efficient train order delivery device of the character arranged to be located at the railway station or elsewhere closely along the line of travel 5 of the locomotive and adapted to detachably support an order sheet holder in position to be readily engaged by the projected arm of the engineer or other train man.

Generally stated, the invention consists of the novel devices and combinations of devices herein-after described and defined in the claims.

The invention involves various novel features but chiefly resides in the novel construction involved in the means for detachably supporting 15 the order sheet holder from a mast or post, which latter is supported at its lower end preferably by an anchoring structure which also involves novel features.

Generally stated, the objects of the invention 20 are simplicity of construction, reliability of action, and elimination of danger to the engineer in the operation of engaging and removing the order holder from the mast.

In the accompanying drawings which illustrate 25 the invention and wherein like characters indicate like parts throughout the several views—

Fig. 1 is a view chiefly in elevation with some parts sectioned;

Fig. 2 is a fragmentary view looking from the 30 left toward the right in respect to Fig. 1 and showing the upper portion of the mast and the elements applied and connected thereto;

Fig. 3 is a horizontal section taken on the line 3—3 of Fig. 2;

Fig. 4 is a horizontal section taken on the line 35 4—4 of Fig. 2;

Fig. 5 is a horizontal section taken approximately on the line 5—5 of Fig. 2; and

Fig. 6 is an enlarged section taken on the line 40 6—6 of Fig. 1.

The mast 7, which is preferably of quite light 45 wooden structure, is provided at its lower end with a rigidly secured metal sleeve 8, the lower end of which projects so that it is adapted to be telescoped over an upstanding anchoring stud 9, the lower end of which is rigidly secured to the bottom of a cup-shaped anchoring base 10 that will be embedded in the concrete 11 or other structure of the platform or roadbed at a point 50 properly offset from the line of travel of the locomotive.

To hold the mast 7 against rotation, the lower 55 end of sleeve 8 is slotted at 12 so as to straddle lugs 13 projected from the opposite sides of the stud 9. The stud 9, it will be noted, does not

project to the top of the anchoring base 10 and the latter is provided with a hinged cover 14. When the mast is removed and the cover 14 is dropped, the base is then protected against the entrance of snow, dust and rain. Also anchor 10 is shown as provided in its bottom with drain passages 15.

The order sheet holder is made of a light tough material such as bamboo that is bent to form a hoop 16 with a depending stem 17. The end of the 10 hoop 16 that crosses the stem 17 is rigidly and permanently secured or tied thereto by suitable means such as a wire 18 bent and wound around the overlapped portions. This wire 18 is also bent to form a clamping clip or projection 19 that 15 presses against the base of the hoop 16 and is adapted to frictionally but securely hold an order sheet 7 such as shown by dotted lines in Figs. 1 and 5.

The stem 17 is arranged to be detachably held to 20 the upper portion of the mast 6 by means of upper and lower holders applied on the mast. These upper and lower holders are applied at both sides of the mast for a purpose which will hereinafter appear. The lower holders are preferably 25 in the form of shallow sockets 20 formed on a split or divided clamping collar 21, which as shown, is clamped to the mast by nut-equipped bolts 22. The upper holders are afforded by spring-acting grapples 23 which, as shown, are 30 secured to the opposite sides of a split clamping collar 24, which, as shown, is clamped to the extreme upper end of the mast by nut-equipped bolts 25. These grapples 23 are of course, aligned one with each of the lower holders or sockets 20. 35 The said grapples 23, as best shown in Fig. 3, have inwardly bent spring ends inwardly spaced and curved to hold and quite firmly grip the stem 17.

The upper split collar 24 is formed with abutments that are engageable with the base-forming 40 portion of the hoop 16 to thereby hold the hoop projected in a vertical plane at right angles to the track and to the line of travel of the train thereover. These abutments may be formed in different ways, but are very economically and efficiently formed by upwardly projected substantially rectangular portions 26 of the clamping collar 24. These angular portions 26 are spaced from each other in a plane at right angles to the track and each is formed with vertically extended 45 abutment-forming portions 27 and 28. In respect to Fig. 2, the right-hand abutments 27 are spaced from the vertical axis of the post 6 a considerably greater distance than are the abutments 28. This is done for the following reason: 50 55

The base-forming portion of the hoop 16 is looped at one side of the stem-forming portion and hence offset therefrom, as well shown in Fig. 2. Hence, when the order sheet holder is applied as shown by full lines in Fig. 2, the base of the hoop will be farther from the axis of the mast than when applied to the opposite side of the mast, as shown by dotted lines in Fig. 2. Here it will be noted that the offset of the abutments 27 is such that they will engage the base of the hoop at points on opposite sides of the stem 17 when the holder is applied as shown at the right, and at which time it will be in a position to be engaged by the projected arm of an engineer of an engine travelling in a certain direction, which may be assumed to be toward the south. When the holder is applied as shown by dotted lines in Fig. 2 and held in a direction to be engaged by the projected arm of the engineer or fireman, the base of the hoop will be near to the axis of the mast and at such time will be engaged on opposite sides of the stem 17 by the abutments 28 and properly held with the hoop projected at right angles to the track.

In either case above considered, the base of the hoop and its laterally projected end will be engaged by two abutments, one on each side of the stem 17 and the hoop will thus be held in the proper projected plane at right angles to the track and will be held against rotation as long as the stem is held by the grapples or frictional holders 23, see particularly Figs. 1 and 2.

It is, of course, of the utmost importance that the holder be so securely held that it will not be dislodged by the action of the wind or otherwise, and while that, it will not offer any considerable resistance for removal when the hoop is engaged by the projected arm of the engineer or fireman. Hence, the following action is highly important, to wit:

When the projected portion of the hoop is engaged by the arm, the first effect of the force applied thereto is to rotate the hoop on the axis of its stem 17, and this rotation will force the projected end or the base of the hoop under an increased pressure against one or the other of the abutments, and the latter, acting as a fulcrum, will cause the upper portion of the stem to be instantly and quickly disengaged from the engaging grapple 23 by forcing the stem to move directly outward or away from the mast. Of course, when the upper portion of the stem is disengaged from the upper grapple, its lower end will be freely removed from the lower holder or socket 20.

In view of the above action of the hoop on the abutments, very light force applied to the projected portion of the hoop will insure certain release from the holding grapples or devices, even when the latter and particularly the grapple 23 is set to very firmly hold the stem against accidental displacement. The arrangement described is not only a simple structure capable of being produced at small cost, but provides an efficient device for securing the order sheet holder in

position to be dislodged from engines moving in either direction along the track. As already indicated, when the device is not to be used for any considerable time, the mast may be easily and quickly removed from its anchoring base.

5

Certain of the advantages of this device may be summarized as follows: It removes possibility of injury of employees, such as operators, being struck by locomotives due to misjudgment of clearance caused by weather conditions, steam escaping from the engines or being blinded by headlights, when required to hand up train order hoops. It removes possibility of injury to the engineer by reason of over-reaching for an order hoop or by failure of the hoop to quickly release. It enables the engineer, even when travelling at high speed, to pick up the hoop with certainty. The mast provides for the safe delivery of train orders to both engine men and train men and the moment the device serves its purpose, it can be placed out of the way, leaving no object to interfere with traffic or persons on or about the depot premises. Of course, means for holding various devices such as a flashlight or a lantern on the mast may be provided when desired.

25

The preferred form of the device has been described in detail, but it will be understood that various modifications thereof may be made within the scope of the invention herein disclosed and claimed.

30

What I claim is:

1. A train order delivery device comprising a mast, a hoop having a depending stem, said mast having upper and lower releasable stem holders and adjacent abutments, the latter being located to engage the base of the hoop and normally hold the same against rotation, but serving as fulcrum-acting abutments when the hoop is engaged and said stem oscillated.

2. The structure defined in claim 1 in which there is an upper and a lower stem holder on the mast, the latter being in the form of a socket and the former being in the form of a spring-acting grapple from which the stem will be disengaged by a rocking movement of said hoop and rotation of said stem.

3. The structure defined in claim 1 in which the stem holders and abutments on said mast are substantially duplicated on opposite sides of the mast so that said hoop may be disengageably held to the mast on either side of the mast for disengagement by an operator of a train travelling in either direction.

4. The structure defined in claim 1 in which the lower stem holder on the mast is in the form of a socket and the upper holder is in the form of a spring-acting grapple from which the stem will be disengaged by a rocking movement of said hoop and rotation of said stem, the said stem holders and abutments being substantially duplicated on opposite sides of the mast for the purpose set forth.

CARL S. ADAMS.
